Inventor

UNITED STATES PATENT OFFICE.

CHARLES A. MCCANN, OF KINGSTON, NEW YORK.

DESIGN FOR A SAW-HANDLE.

SPECIFICATION forming part of Design No. 19,904, dated June 10, 1890.

Application filed April 25, 1890. Serial No. 349,505. Term of patent 14 years.

To all whom it may concern:

Be it known that I, CHARLES A. MCCANN, a citizen of the United States, residing at Kingston, in the county of Ulster and State 5 of New York, have invented a new and original Design for Saw-Handles, of which the following is a specification.

My design consists, essentially, of a saw-handle provided with two ellipsoidal openings 10 arranged one above the other, the major axes of said openings forming an angle of between forty-five and ninety degrees.

In the drawing illustrating my invention, A indicates a saw having the handle B.

15 C and D are ellipsoidal hand-openings in the handle B, said openings being arranged the one above the other in such a manner that when the major axis of D is produced it forms an interior angle with the major axis of C, be- 20 tween forty-five and ninety degrees.

E and F are the usual rounded hand-grips tapering off into the horns x, y, and z.

1, 2, and 3 are countersunk bolt-holes.

The two sides of the handle are similar.

The form of my design is that shown in the 25 drawing, in which there are no sharp points at the horns and no deep or irregular indentations in the general outline, the same being composed of Hogarthian and other wavy lines.

Having thus described my invention, what I 30 claim as new, and desire to secure by Letters Patent, is—

The design for a saw-handle herein described and shown.

In testimony that I claim the foregoing as 35 my own I have hereto affixed my signature in presence of two witnesses.

CHARLES A. MCCANN.
